ATTORNEY

UNITED STATES PATENT OFFICE

2,407,770

LIQUID APPLICATOR

Isabelle H. Daniel, Los Angeles, Calif.

Application March 18, 1943, Serial No. 479,611

2 Claims. (Cl. 91—27)

1

This invention relates to means and methods for applying paints, lacquers, and other liquids and semi-liquids to tubes, pipes, etc., and to all kinds of rounded, flat and irregular surfaces.

The invention has been found most useful in applying lacquers and the like over labels and identification stickers upon tubes, conduits and cables. All varieties of pipes and tubes used in a completed airplane are marked by a variety of colored labels which are stuck to the pipes and tubes by an adhesive of some kind. These labels must be protected so that the pipe or tube does not lose its identification, therefore, the label and a marginal portion of the pipe or tube adjacent thereto is coated with a transparent lacquer.

The device of this invention is designed to quickly and evenly apply the lacquer to the labels and near portions of adjacent surfaces, and making a weather-seal that is very satisfactory in accordance with the specifications of the airplane industry.

One of the principal objects of the invention is to present a liquid or semi-liquid coating device that applies the liquid or semi-liquid to the surface to be coated by a rolling action, means being convenient to remove all the surplus liquid or semi-liquid from the surface as same has been thoroughly and evenly covered.

Another object is to provide a paint or lacquering device that is easy to be operated by unskilled hands, efficient in operation, simple in construction, and economical to manufacture.

Other objects, advantages and features of my invention will appear from the accompanying drawing, the subjoined detailed description, the preamble of these specifications and the appended claims.

Applicant is about to illustrate and describe one of the forms of her invention in order to teach one how to make and use the same, but it is to be understood that the drawings and description thereof are not to limit the invention in any sense whatsoever, except as limited by the appended claims.

In the drawing:

Fig. 1 shows the invention in side elevational view, with portions thereof broken away to show interior structural details.

Fig. 2 is a plan view with the cover or lid removed.

Fig. 3 is an elevational view showing the results obtainable when the inventive device is properly used.

The device, as illustrated, comprises a base or

2

well unit 1 and a cover or lid 2; the base having a bottom wall 3, short end walls 4 and 5, and side walls 6 and 7, all the walls preferably being integral to form a liquid well 8. The cover has the integral top, and side depending walls 9, 10, 11, 12 and 13 respectively, to form an inverted receptacle-like protector adapted to fit the top edges of the side walls of the base 1 and protect all the elements mounted near the top thereof. In order that the cover will form a fairly good hermetic seal with the base and prevent evaporation of the liquid in the well, the depending sides of the cover are rabbeted at 14 so as to provide a shoulder to receive the top edges of the base, as shown. A chain or cord 15 holds the cover near the base when the cover is removed.

The bottom of the base 1 has a short tube or socket 16 welded or brazed thereto, into which is threaded the stem of a wing nut 17. In the bore 20 of the socket is one end of an offset rod 18, this rod extending from any suitable support, such for instance, as the wall of the building, table top, work bench, or from some part of some machine that might be used in conjunction with the device of this invention. The purpose of the tube 16 is to provide a pivot for the device so that it can be adjusted to an inclined position to facilitate its usefulness, and especially when it is an advantage to tilt the device for lacquering some odd shaped pipes and rods.

On the inner side of each wall 6 and 7 there is an embossed portion having parallel ribs 19 and 20, these ribs forming a rounded bearing 21 where they join together at their lower ends. The space between the ribs provides a guideway 22 to accommodate the axle 23 of a roller 24. This construction allows the roller to be removed readily from the well for cleaning and replacement. Wrapped around the curved periphery of the roller is a felt pad 25. In the surface of the roller is an elongated cross slot 26, this slot being of such a size that it will snugly receive the ends of the felt pad and thus hold the pad tautly onto the roller in a manner that it can be removed readily whenever desired.

Also mounted in the well is a brush 27, which may be of the spiral type, the center of the brush having the rod 28 into which are fixed the bristles of the brush, and also the supporting screws 29 and 30, these screws passing through the sides of the base and holding the brush stationary in the well.

Any kind of materials suitable for the purposes may be used in the construction of the liquid and semi-liquid coating device of this invention. The

entire base and lid may be cast from metal or formed from plastics, if desired. The roller may be made of plastic or made of wood. The entire base can be molded as a single unit.

When the device is used for coating lacquer around a pipe and over a label that has been cemented thereto, the cover 2 is obviously removed and the pipe placed at or about the position 31 as shown in dotted lines in Fig. 1 of the drawing. If the pipe is turned as indicated by the arrow, the roller 24 will rotate as indicated by its arrow, this rolling motion will cause the felt 25 to carry lacquer upwardly from the well and contact the surfaces of the pipe 31 which are brought into contact with the felt pad. Since the felt is usually wet with lacquer, because of a previous use, one complete rotation of the pipe will deposit an even film of lacquer around the pipe. When this operation has been completed, the pipe is brought into contact with the stationary brush 27 and given a twist to remove all surplus lacquer from the pipe. Fig. 3 shows a pipe 31 that has been treated by applicant's device. The lacquer, indicated at 32, completely covers a label 33 which has been previously cemented to the pipe. Note that the lacquer also covers a portion of the pipe beyond the confines of the label.

Having thus described my invention, what is

claimed as new and desired to be secured by Letters Patent is:

1. In a device for coating a liquid substance on the outer surfaces of pipe and the like, the device comprising a base having a bottom, opposed upstanding end walls, and upstanding side walls to form a reservoir for liquid, a roller with an absorbing covering having its ends removably journaled in the side walls and positioned so that top portions thereof extend above the tops of the side walls and its bottom portions dip into the reservoir, a cylindrical brush having long bristles and rotatably mounted for adjustment to a fixed operative position on an axis mounted in the side walls so that the longitudinal axis of both roller and brush are parallel, the roller and brush being so spaced apart that their near surfaces can conjointly support the pipe to be coated and so that when the pipe is rotated the roller is rotated.

2. The device recited in claim 1 wherein the base has a socket fixed to the underside thereof, a rod in the socket having an end to be extended and fixed to a support, and a finger adjustable means for securing the rod in the socket, said socket allowing the device to be adjusted around the rod and be tilted to any desired angle.

ISABELLE H. DANIEL.
